UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN LASTING SHOES.

Application filed January 21, 1922. Serial No. 530,968.

This invention relates to the lasting of boots and shoes, and is herein illustrated in its application to the lasting of the shank portion of tennis shoes or "sneakers" in the manufacture of which it is customary to fasten the margin of the upper in lasted relation to the insole by adhesion through the use of cement. It will be evident, however, that in many of its aspects the invention is not limited to shank lasting nor restricted to the manufacture of any particular type of shoe.

In the manufacture of tennis shoes and other like shoes the bottoms of which are made of rubber or rubber composition it has been the usual practice heretofore to perform the lasting operation entirely by hand, the workman using his fingers to work the upper over the last and to press its margin into adhering relation to the insole. Recently, however, machines have been devised for lasting in a more satisfactory and expeditious manner the foreparts and the heel end portions of rubber soled shoes. Such machines for forepart and heel end lasting respectively are shown, for example, in Letters Patent No. 1,541,820, granted upon my application on June 16, 1925, and in Letters Patent No. 1,634,502, granted upon my application on July 5, 1927.

It is an object of the present invention, among others, to provide a machine by the use of which the shank portion, for example, of shoes of the above mentioned and other types may be lasted more quickly, easily and satisfactorily than heretofore. As herein illustrated, the lasting operation is performed by presenting the side of the shoe in engagement with a driven lasting tool in such relation that the upper engaging face of the tool moves over the surface of the upper in a direction transverse to the edge of the shoe bottom, and by then turning or rocking the shoe to render the tool progressively effective to work the upper tightly into conformity to the contour of the last about the edge of the shoe bottom and to bend the margin of the upper inwardly upon the bottom face of the insole. In the lasting of shoes in which the margin of the upper is fastened to the insole by cement the upper is thus drawn tightly over the last while its

margin is out of contact with the bottom face of the insole, and by the turning of the shoe the margin of the upper is then bent inwardly into substantially parallel relation to the bottom face of the insole so that it adheres to said face.

The machine herein shown comprises, among its important features, a novel construction and arrangement of lasting means and shoe positioning means designed for working the upper into lasted position through turning or rocking movement of the shoe, the construction shown comprising a shoe supporting member which is mounted for turning movement with the shoe relatively to a lasting tool to transfer the area of effective engagement of the tool with the upper toward the bottom edge of the upper. For the purposes of side or shank lasting, as illustrated, the shoe positioning means is mounted to turn about an axis extending lengthwise of the shoe and intersecting the shoe on a line which is substantially or approximately the center of curvature of the shank portion of the shoe in a plane perpendicular to the shoe bottom, so that the turning of the shoe for the purposes in view may be effected without substantial bodily displacement of the shoe. While in many of its aspects the invention is not limited in respect to the character of the lasting means, a tool which is effective and advantageous for the purposes of the invention comprises a driven roll, as herein shown, constructed for frictional engagement with the upper to work it into lasted position. Novel features of the invention are also to be recognized in the construction of the lasting roll, including provision for yield in conformity to the shape of the shoe and provision for insuring adequate friction between the roll and the upper. For the purposes of shank lasting the roll herein shown has a convex peripheral curvature lengthwise of its axis to conform approximately to the concavity at the shank of a shoe and is of such length as to engage the upper substantially from the ball to the heel seat and thus to last the entire shank at each side of the shoe at a single operation.

As a further important feature, the invention provides novel means for controlling

the insole in the lasting operation, the construction shown comprising a member which is mounted to turn with the shoe and serves to hold the insole closely against the bottom of the last where the margin of the upper is lasted inwardly over it. This insures that the margin of the upper as it is wiped inwardly, for example, by the lasting means will not adhere prematurely to the insole and thus interfere with the proper shaping of the shoe in the shank and also prevents danger of upturning or otherwise displacing the margin of the insole by the wiping pressure. In shank lasting such control of the insole is particularly important because of the tendency of the insole not to lie in close conformity to the concave curvature of the last bottom, or in other words to "bridge" from the ball to the heel seat.

The novel features of the invention, including those hereinabove set forth, together with various details of construction and combinations of parts, will now be more particularly described with reference to the accompanying drawings and pointed out in the claims.

In the drawings:

Fig. 1 is a perspective view of the head portion of a machine in which features of the invention are embodied;

Figs. 2 and 3 are vertical sections through the shoe support and the shank portion of a shoe on said support, illustrating different positions of the support and the shoe in relation to the lasting tool in the course of the lasting operation, and

Fig. 4 shows the shoe and the lasting tool in substantially the same relation as in Fig. 2 as viewed from a point underneath the shoe.

The machine comprises a supporting standard 2 upon the top of which is rotatably mounted a shaft 4 arranged to be driven by a belt on a pulley 6 and carrying on one end a lasting roll 8. This roll in the machine shown is of such length as to extend substantially from the ball line of the shoe rearwardly to the heel seat so as to last at one operation the entire shank portion of the shoe at either side. Moreover, as shown in Fig. 4, the periphery of the roll 8 is convex in the direction of the length of the roll to conform approximately to the concavity of the shank of the shoe lengthwise of the shoe. While the tool, in many of the aspects of the invention, may be variously constructed for the purposes in view, a novel and advantageous construction for effecting frictional engagement with the upper to tighten it over the last and work it inwardly over the insole comprises a band 10 of rubber which forms the peripheral portion of the roll and is provided with corrugations 12 extending lengthwise of the roll, the corrugations in the construction shown extending

substantially parallel to the axis of the roll. In operation the roll 8 is driven continuously in the direction of the arrow *a*.

For presenting the shoe to the lasting roll the machine is provided with a shoe support comprising a pair of arms 13 which are fast on a rock shaft 14 mounted in a bearing in a bracket 16 which is vertically adjustable on the standard 2 and is held in adjusted position by tie bolts 18. Mounted on pivots 20 on the upper ends of the arms 13 is a stirrup-shaped shoe rest member or holder 22 upon which the shoe is positioned for the shank lasting operation. The member 22 carries a plate 24 provided with an upwardly bent end having a convex edge face 26 for engagement with the insole of the shoe in the shank, as illustrated in Fig. 2. The plate 24 is adjustable lengthwise and is held in adjusted position by means of a bracket 28 which serves to support an additional T-shaped shoe rest member 30 for engagement with the shoe on the opposite side from the roll. The member 30 is held in position by a clamping bolt 32 and may be adjusted by turning it, by sliding it up or down, or by swinging it toward or from the roll. The shoe support when not in use is maintained in a forwardly tipped position by means of a spring 34, the limit of such forward movement being determined by a stop screw 36 which is carried by a depending lug on the swinging support and is arranged to engage the bracket 16. To assist in swinging the support toward the lasting tool, one of the arms 13 is provided with a member 38 which is adapted to be engaged by the hip of the operator as he presents a shoe to the machine. Movement of the support toward the lasting tool may be limited by a stop screw 40 which is threaded in one of the arms 13 and is arranged to engage the bracket 16.

In the use of the machine illustrated for lasting the shank portion of a rubber soled shoe which has been previously lasted at the forepart and the heel end by the use, for example, of machines shown in the prior Letters Patent hereinbefore mentioned, the shoe is presented in engagement with the positioning members 24 and 30 substantially as illustrated in Fig. 2, these members having been previously adjusted in accordance with the size of the shoes to be lasted in such manner that each shoe may be conveniently presented to them with the convex edge 26 of the sole rest plate 24 engaging the shank of the insole in a location near that side of the shoe that is toward the lasting roll but preferably farther from the edge of the insole than the margin of the upper is to extend when it is wiped inwardly. It will be understood that the shoe rest member 22 will hang substantially vertical when the shoe is presented to it, and

after the shoe has been positioned upon the members 24 and 30 the member 22 will be tipped forwardly by the operator so that the side of the shoe may be presented in engagement with the lasting roll at a distance from the bottom edge of the upper, as illustrated in Fig. 2. In thus presenting the shoe the operator will preferably engage it with both hands at its opposite ends and will effect the tipping or turning of the shoe rest member 22 through the shoe. As the operator tips the shoe into the position illustrated in Fig. 2 he swings the support rearwardly toward the lasting roll by engagement 5 of his hip with the member 38. As the roll engages the side of the shoe it acts frictionally to draw and press the upper into conformity to the contour of the last. While holding the shoe in engagement with the roll 10 the operator turns the shoe with its supporting member 22 in the direction of the arrow *b* to the position illustrated in Fig. 3, thus effecting a transfer of the area of effective engagement of the roll with the upper toward the bottom edge of the upper and rendering the roll effective as it draws and holds the upper tightly in conformity to the contour of the last to bend its margin inwardly into parallel relation to the bottom 15 face of the insole and to press it upon said face so that the cement previously applied to the upper or the insole becomes effective to fasten the upper in lasted position. It will be noted that the axis of turning movement of the shoe, represented by a line connecting the pivots 20, is substantially parallel to the axis of the roll 8 and intersects the shoe substantially or approximately at the center of curvature, in a plane perpendicular to the shoe bottom, of that portion 20 of the shoe upon which the roll acts in the lasting operation, so that the shoe may be turned as required without any substantial bodily displacement of it, the operator 25 simply maintaining pressure on the member 38 to hold the support as a whole in shoe presenting position. By reason of the lengthwise convexity of the peripheral surface of the roll and the yielding character 30 of the rubber, the roll conforms substantially to the lengthwise curvature of the shank of the shoe and is effective to work the upper tightly into lasted position at all portions of the shank. Having performed the lasting 35 operation in this manner at one side of the shoe, the operator permits the shoe support to swing forwardly, and having reversed the shoe end for end presents the other side of the shoe to the lasting roll to complete the lasting at that side of the shoe. The shoe is then completely lasted and is ready for the sole laying operation.

As the shoe is turned to render the roll effective to lay the margin of the upper inwardly over the insole, the sole rest mem-

ber 24 has an important function, not only in holding the marginal portion of the insole from displacement by the inwardly directed lasting pressure of the roll, but also in pressing the insole closely against the bottom of the last in the inward curve at the shank, thus preventing premature adhesion between the upper and the insole such as might occur if the margin of the insole were unduly separated from the bottom of the last, which would render it difficult if not impossible to draw the upper tightly into conformity to the contour of the last after the shoe had been turned far enough to bring the pressure of the roll to bear upon the bottom face of the insole. By the action of the member 24 the insole is held in such close relation to the bottom of the last that the upper is conformed closely and tightly to the contour of the last before its margin begins to adhere to the insole.

The novel method of lasting herein disclosed is claimed in a divisional application, Serial No. 153,401, filed on December 8, 1926.

Having described the invention, what I claim as new and desire to secure by Letters Patent of the United States is:

1. A machine of the class described having, in combination, lasting means constructed to work an upper into lasted position by progressive action along the surface of the upper, and a shoe positioning device mounted for turning movement with a shoe to transfer the area of effective engagement of said lasting means with the upper progressively toward the bottom edge of the upper.

2. A machine of the class described having, in combination, a lasting tool constructed to work an upper into lasted position by progressive action along the surface of the upper, and a shoe support movable to carry the side of a shoe into engagement with said tool and comprising a member mounted to turn with the shoe about an axis extending lengthwise of the shoe to render the tool progressively effective to bend the margin of the upper inwardly over the bottom of the last.

3. A machine of the class described having, in combination, lasting means constructed to act frictionally on an upper to work it into lasted position, and a shoe positioning device mounted to turn with a shoe about an axis that intersects the shoe to render said lasting means progressively effective to bend the margin of the upper over the edge of the insole and then to lay it in parallel relation to the bottom face of the insole.

4. A machine of the class described having, in combination, side lasting means, and a shoe support arranged to present the side of a shoe in engagement with said lasting means and comprising a member mounted to turn with the shoe about an axis which ex-

tends lengthwise of and intersects the shoe to render the lasting means effective to work the upper progressively over the edge of the shoe bottom and into parallel relation to the 5 bottom face of the insole.

5. A machine of the class described having, in combination, a lasting tool, and shoe positioning means arranged to present the side of a shoe in engagement with said tool 10 and comprising a member mounted to turn with the shoe about an axis extending lengthwise of the shoe approximately at the center of curvature, in a plane perpendicular to the shoe bottom, of that part of the 15 shoe which is presented in engagement with the tool.

6. A machine of the class described having, in combination, lasting means constructed to act progressively along the surface of 20 an upper to work the upper into lasted position, and a shoe positioning device movable with a shoe toward said lasting means, said shoe positioning device being constructed to permit turning movement of the shoe in 25 engagement with the lasting means to bend the margin of the upper inwardly over the insole into substantially parallel relation to the bottom face of the insole.

7. A machine of the class described having, in combination, a frictional lasting tool, and a shoe support constructed and arranged to be moved by the operator to present a shoe in engagement with said tool, said shoe support comprising a member arranged to be turned by the operator as he holds the support in shoe presenting position to transfer the area of effective action of the tool progressively toward the bottom edge of the upper and to bend the margin 40 of the upper inwardly over the insole.

8. A machine of the class described having, in combination, side lasting means, and a shoe support constructed to be engaged and moved toward said lasting means by pressure of the operator's hip against it, said shoe support including a shoe positioning device mounted to turn with the shoe about an axis extending lengthwise of the shoe to bring different portions of the shoe within 50 the field of action of the lasting means.

9. A machine of the class described having, in combination, a side lasting tool, and shoe positioning means constructed to position a shoe with its side toward said tool 55 and comprising a stirrup-shaped member mounted to turn about an axis extending lengthwise of and through the shoe to render the tool progressively effective to work the upper down the side and inwardly over the bottom of the last.

10. A machine of the class described having, in combination, a side lasting tool, and a shoe support arranged to present a shoe with its side toward said tool and upon 65 which the shoe may be reversed end for end

to present its opposite sides toward the tool, said shoe support comprising a shoe positioning member mounted to turn with the shoe in either position of the latter about an axis that extends lengthwise of the shoe 70 to render the tool progressively effective to work the upper down the side and inwardly over the bottom of the last.

11. A machine of the class described having, in combination, a side lasting tool, and a 75 shoe support comprising members constructed and arranged to engage the shoe respectively upon its bottom and upon one side for presenting the other side of the shoe to the tool, said members being mounted to turn with the shoe about an axis extending lengthwise of the shoe to render the tool progressively effective upon different portions of the upper.

12. A machine of the class described having, in combination, a frictional side lasting tool, and a shoe support comprising members constructed and arranged for engagement respectively with the bottom and a side 90 of the shoe and upon which the shoe may be reversed end for end to present its opposite sides to the tool, said members being relatively adjustable for shoes of different sizes.

13. A machine of the class described having, in combination, a frictional lasting tool, and shoe positioning means constructed to present a shoe to said tool and to turn with the shoe to render the tool effective to bend the margin of the upper inwardly over the insole comprising a member arranged to engage the insole near that portion of its margin where the upper is bent inwardly by the tool to hold the insole closely upon the bottom of the last.

14. A machine of the class described having, in combination, side lasting means, and a shoe positioning device constructed and arranged to position a shoe with its side toward said lasting means and to permit turning of the shoe to render the lasting means 110 effective to bend the margin of the upper inwardly into adhering relation to the bottom face of the insole, said shoe positioning device comprising a member arranged to engage the insole near its side edge to prevent displacement of the insole by the lasting means.

15. A machine of the class described having, in combination, a side lasting roll constructed to act frictionally on the upper at 120 the shank of a shoe, and a shoe positioning device constructed to permit turning of the shoe about an axis extending lengthwise of the shoe to render the roll effective to wipe the margin of the upper inwardly into adhering relation to the insole, said shoe positioning device comprising a member arranged to engage the shank portion of the insole as the shoe is turned and to press the insole into the shank curvature of the last bot- 125 130

tom to prevent premature adhesion of the upper to the insole.

16. A machine of the class described having, in combination a side lasting tool for laying the margin of an upper inwardly over the bottom of an insole on a last, and a shoe support constructed and arranged to position a shoe with its side toward said tool and having thereon a member for engaging the insole in a position to prevent displacement of the margin of the insole by the action of the lasting tool and another member arranged to afford a rest for the opposite side of the shoe from that on which the tool is acting.

17. A machine of the class described having, in combination, a frictional lasting tool, and a shoe support comprising a stirrup-shaped member mounted to turn with the shoe about an axis extending lengthwise of the shoe to render the tool progressively effective upon different portions of the upper and having thereon a pair of shoe rest members arranged to engage the side and the bottom of the shoe respectively and upon which the shoe may be reversed end for end to present either side to the lasting tool.

18. A machine of the class described having, in combination, lasting means constructed to act upon substantially the entire length of the shank of a shoe at one operation, and means for presenting a shoe to said lasting means mounted to turn with the shoe about an axis extending lengthwise of the shoe to render said lasting means progressively effective to work the upper inwardly in the shank and over the margin of the insole.

19. A machine of the class described having, in combination, frictional lasting means constructed to conform approximately to the curvature of the shank of a shoe lengthwise of the shoe and to engage the side of the shoe substantially continuously from the ball to the heel seat, and means for presenting a shoe to said lasting means comprising a member mounted to turn with the shoe to render the lasting means progressively effective to wipe the upper into the shank and over the margin of the insole.

20. A machine of the class described having, in combination, a frictional lasting tool constructed for engagement with the upper at the shank of a shoe to wipe the upper over the side of the last and inwardly into position to adhere to an insole on the bottom of the last, and a shoe support movable in a direction widthwise of the shoe to present the shoe to said lasting tool comprising a member arranged to engage the insole at the shank and to press the insole toward the bottom of the last to prevent premature adhesion between the insole and the margin of the upper.

21. A machine of the class described hav-

ing, in combination, a frictional lasting roll, means for rotating said roll, and a shoe support arranged to present a shoe with its upper in engagement with said roll, said shoe support being constructed to permit turning movement of the shoe to transfer the area of effective engagement of the roll with the upper toward the bottom edge of the upper.

22. A machine of the class described having, in combination, a driven rotary lasting tool, and a shoe support mounted to turn about an axis substantially parallel to the axis of said tool to transfer the area of effective engagement of the tool with the upper progressively toward the bottom edge of the upper.

23. A machine of the class described having, in combination, a driven rotary lasting tool constructed for frictional engagement with an upper, and a shoe support constructed and arranged to present a shoe with its side toward the periphery of said tool and to turn with the shoe about an axis extending lengthwise of the shoe to render the tool effective to wipe the upper inwardly over the bottom of the last.

24. A machine of the class described having, in combination, a rotary lasting tool constructed for engagement with the side of an upper substantially from the ball to the heel seat and having a convex curvature lengthwise of its axis to conform approximately to the inward curvature of the shoe at the shank, and means for presenting a shoe to said tool constructed to permit turning of the shoe to render the tool effective to wipe the upper progressively inward over the insole.

25. A machine of the class described having, in combination, a driven lasting roll constructed to act frictionally on an upper at the shank to wipe the upper over the last and inwardly into adhering relation to the insole, said roll having a peripheral curvature lengthwise of its axis to conform approximately to the shank curvature of the shoe, and shoe positioning means constructed to permit turning of the shoe in engagement with said roll.

26. A machine of the class described having, in combination, a lasting roll having a corrugated rubber periphery adapted to act frictionally on an upper, and means for presenting a shoe to said roll constructed to permit turning of the shoe to render the roll progressively effective to bend the margin of the upper inwardly over the insole and to wipe it into parallel relation to the bottom face of the insole.

27. A machine of the class described having, in combination, a driven lasting roll having a convex peripheral curvature lengthwise of its axis approximately complementary to the lengthwise shank curvature of a shoe

to adapt it to act in the shank of a shoe to wipe the upper transversely of the edge of the shoe bottom and having a peripheral portion of yieldable material to permit further conformation to the shape of the shoe, and a shoe support movable to present a shoe with its side face in engagement with said roll.

28. In a machine of the class described, a lasting roll adapted to act frictionally upon the upper of a shoe to wipe the upper into lasted position, the shoe engaging peripheral face of said roll extending lengthwise of its axis a sufficient distance to permit the roll 10 to act upon substantially the entire length 15 of the shank of the shoe at one operation and

having a convex curvature lengthwise of the axis of the roll to conform approximately to the inward curvature of the shank of the shoe.

29. In a machine of the class described, a lasting roll having a peripheral portion of material which is yieldable in response to pressure of a shoe upon it and convexly curved lengthwise of the axis of the roll 20 to adapt the roll to operate in the shank of the shoe, said roll being of such length as to engage the shoe continuously throughout substantially the entire length of the shank.

25 In testimony whereof I have signed my name to this specification.

BERNHARDT JORGENSEN.
